(57) **CLAIM**

The ornamental design for a dual grip container, as shown and described.

DESCRIPTION

FIG. 1 is an isometric view of a dual grip container; FIG. 2 is a front view of the dual grip container, the back view being identical thereto;

FIG. 3 is a left side view of the dual grip container, the right side view being identical thereto;

FIG. 4 is a top view of the dual grip container; and, FIG. 5 is a bottom view of the dual grip container.

The broken lines showing top inner, top outer, and bottom surfaces illustrate portions of the dual grip container or environmental structure and form no part of the claimed design.

1 Claim, 5 Drawing Sheets(56)
